CIGAR BUNCH SEPARATING MECHANISM

John F. Halstead, Brooklyn, N. Y., assignor to
International Cigar Machinery Company, a
corporation of New Jersey

Application May 17, 1940, Serial No. 335,657

4 Claims. (Cl. 131—81)

This invention relates to bunch-charge separating mechanism for cigar machine, and an object of the invention is to improve the method of ejecting the charge from the magazine after cutting the same from a tobacco column.

In my co-pending application S. N. 237,254, filed Oct. 27, 1938, on which Patent No. 2,255,740 dated Sept. 9, 1941 was granted, the bunch charge, upon being cut, is tightly held between the bottom plate of the tobacco magazine and the separator plate which advances with the knife and supports the vertical tobacco column from which the charge has been cut. Therefore the plunger used to expel the cut charge from the magazine meets with so great a resistance that it has to advance some distance (about one-third the width of the magazine) into the charge before the latter starts to move. This movement under considerable pressure causes a disturbance of the charge which results in faulty bunches.

In order to obviate this difficulty in the embodiment of the invention selected to illustrate the invention there is provided mechanism for lowering the bottom plate of the magazine a certain distance after the charge has been cut, thereby creating a clearance between the cut charge and the separator plate, and thus eliminating the objectionable friction formerly encountered by the then advancing ejecting plunger. This improved method of charge ejection may be achieved by simply cutting out a portion of the tail of the cam piece shown in Fig. 18 of my prior patent referred to hereinbefore. This change and its effect on the operation of the mechanism is shown in the accompanying drawings in which:

Fig. 1 is an end elevation of charge-cutting and ejecting mechanism, similar to that disclosed in my Patent No. 2,255,740;

Fig. 2 is a top view from line 2—2 of Fig. 1;

Fig. 3 is a side elevation of a portion of Fig. 1; and

Figs. 4 to 11, inclusive, are diagrammatic views showing the operation of the modified device during one cycle of the machine.

Referring to the drawings, the plates 20, 21 and 22 (Fig. 1) which constitute the side walls of a vertical filler supply magazine, designated generally 23, are placed and supported in the same manner as in my above mentioned patent. A pressure plate 24 secured to a slide 26 as shown in my co-pending application is operated to compress the filler tobacco supply held in the magazine 23 by a bottom plate 31 which is attached to a bracket 32 projecting from a slide 33 mount-

ed for vertical movement in the bracket 34 (Fig. 3).

Pressure plate 24 is provided on its tobacco contacting face with a resilient pad 46 which assures a practically uniform density over the whole cross-sectional area of the column of tobacco. When a charge is to be separated, the column of tobacco is held in compression between pressure plate 24 and bottom plate 31 by cam 10 actuated mechanism such as shown in my above mentioned patent and the column of tobacco so held therebetween is lowered into charge separating position, and an adjustable screw 51 carried by a holder 52 secured to the slide 33 in any suitable manner engages a plate 53 attached to the upper end of bracket 34 and stops further descent of the slide 33 and the bottom plate 31. Screw 51 is provided with a graduated barrel which permits the operator of the machine to readily determine the amount of adjustment given to screw 51. The turning of screw 51 regulates the thickness of the charge to be separated and when correctly set it is locked in place by a nut 56.

Referring to Figs. 1 and 2, the charge-cutting knife 71 carried by arms 203, and the column-supporting separator plate 70 are actuated by cam-operated link 201 which turns bell-crank lever 183 fulcrumed on shaft 200 and, through connecting rod 182, controls knife slide 181 to which the cam piece 184 is attached. This cam piece is the same as that shown in Fig. 18 of my prior Patent No. 2,255,740 with the exception that it has a cut-out 204 in its tail portion, the incline 205 near its forward end being the same as before.

The charge-ejecting plunger 74 attached to plunger plate 73 is operated by the slide 155 controlled by cam-actuated link 202 through bell-crank lever 157 and connecting rod 156. To slide 155 is affixed the holder 161 which, on pivot 163, carries the latch 162, the roller 185 of which is held by spring 206 in engagement with the under side of cam piece 184. To cross bar 207 of knife slide 181, which carries the knife arms 203, is attached a link 208 connected to an eccentric driven by one of the shafts of the machine or by a separate small motor, thus imparting horizontal oscillating motion to the knife 71 as the same advances into the tobacco column.

The levers 166 and 168 on fulcrum 167, the link 171, arm 177, adjusting screw 51, filler magazine 23 and all co-acting mechanisms are the same as described in my Patent No. 2,255,740,

The operation of the improved device is as follows:

In Fig. 4 the relative positions of the working parts at the beginning of the cycle are shown. Both the knife 71 and the plunger 74 are in their starting positions and out of the magazine 23. The roller 185 of latch 162 is clear of the incline 205 of cam piece 184, and the latch 162 engages the pin 165 of lever 166.

A depression in the cam track (not shown) which actuates link 202 causes the plunger 74 momentarily to advance a short distance into magazine 23 (Fig. 5) thereby, due to the engagement of the latch 162 with pin 165 forwardly moving the arm 168 approximately to position 168' and through link 171 setting the arm 171 mounted on spindle 178 threaded into and turning in a threaded hub 179 secured in bracket 53 into the proper position 171' (Fig. 5) which sets the position of plate 31 through adjustable stop screw 51, causing the plate 31 to descend and thus increasing the thickness of the thin charge about to be severed from the mass of filler tobacco in magazine 23, as shown in my above mentioned patent preparatory to severance of a bunch charge. Stud 169 of arm 168 is normally held against the end of slot 170 in link 171 by a spring 172 stretched between a post 173 of link 171 and a post 174 carried by an upright column 175. The extent plunger 74 advances into the magazine is controlled by the density of the tobacco, the spring 172 yielding as explained in my previously mentioned patent, while the lever 157 swings to the forward limit of its movement. When plunger 74 is actuated to feel the lower portion of the filler tobacco, it advances into the tobacco until the density of the same overcomes the tension of the spring 172 whereupon any additional travel of the plunger will be stopped as the stud on the upper end of the lever 157 will pass freely in the slot 159. If the tobacco is of the desired density, the slot 159 is long enough to take up the travel of the stud and the plunger will remain inactive. On the return of plunger 74 from its "feeling" stroke, the arm 168 moves back to its original position, slot 170 preventing link 171 from participating in this movement. The link 171 is retained in its forward position, as the adjusting screw 51 bears against a fiber insert 180 provided in spindle 178, thus holding spindle 178 from turning whereby stud 169 will move freely in slot 170.

Next, cam-operated link 201 causes lever 183 to advance knife 71, Fig. 6, thereby moving cam piece 184 in the forward direction, causing the incline 205 to depress roller 185, thus disengaging the latch 162. As the knife continues to advance, the cam piece 184 slides over roller 185 until the latter, when the knife is nearly all the way in, snaps into cut-out 204, re-engaging latch 162, Fig. 7.

As the knife then completes its forward movement, the link 202 commences to ascend. Hence the plunger 74 starts to move in, Fig. 7, the arms 166 and 168 advancing with the same due to the engagement of latch 162, thereby moving the arm 171 into position 171'' (Fig. 8) in which the spindle 178 has turned sufficiently to allow bottom plate 31 of magazine 23 to drop to position 31', Fig. 3, thus providing room for reducing the friction of the movement of plunger 74 after the latter has entered within the magazine.

While the plunger continues to move inward, and because the knife slide has completed its forward stroke, Fig. 8, the roller 185 slides out

of cut-out 204 and entering the under face of cam piece 184, tilts latch 162 and disengages the same, so that the arms 166, 168 remain stationary while the plunger 74 moves all the way in, to eject the cut charge T' when the roller 185 has passed beyond the incline 205 of cam piece 184, Fig. 9.

The plunger 74 then begins its return stroke and, when almost in its outermost position, Fig. 10, the roller 185 snaps into cut-out 204 of cam piece 184, thereby re-engaging latch 162.

As the plunger completes its rearward stroke, Fig. 11, the roller 185 rides on the cut-out 204, and latch 162 pushes arm 168 back into its original position. At this time, plate 31 is moved upward, stopping a short distance below plate 70 to prevent dropping of the column of tobacco in magazine 23 at the time separator plate 70 is withdrawn, as described in Patent No. 2,255,740. This upward movement of plate 31 releases the pressure on screw 172 so that spring 172 can reset the link 171 and lever 171 into its starting position, Fig. 4. Then the knife plate 70 moves back to its starting position, and the plate 31 in conjunction with plate 24 and other parts, moves up to receive a new charge addition to the magazine, as described in my patent referred to above. Thereupon the top plate 24 of the magazine, which has previously ascended to allow the new charge addition to enter magazine 23, moves down to compact the added charge T upon the column of tobacco supported by plate 31, and the mechanism is ready to cut another bunch charge T' from the same, as shown in Fig. 4.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

What is claimed is:

1. In a cigar machine, the combination with means for compacting a column of tobacco, of a knife for severing a bunch charge from the compacted column, a device for determining the density of the column prior to severance of the bunch charge therefrom, mechanism controlled by said device for reducing the pressure with which said column is compacted by said means whenever said device detects an excessive density of the tobacco in said column, a member for ejecting the severed charge from the compacted column, and mechanism for relieving the pressure on the severed bunch charge during the removal thereof by said member.

2. In a cigar machine, the combination with means for compacting a vertical column of laminated filler tobacco, of a horizontal knife for severing a bunch charge from the compacted column of tobacco, a device for determining the density of the column prior to severance of the bunch charge therefrom, mechanism controlled by said device for reducing the pressure with which said column is compacted by said means whenever said device detects an excessive density of the tobacco in said column, a member for ejecting the severed charge horizontally from the compacted column, and mechanism for relieving the pressure on the severed bunch charge during the removal thereof by said member.

3. In a cigar machine, the combination with means for compacting a vertical column of laminated filler tobacco, of a horizontal knife for severing a bunch charge from the lower end of

the compacted column of tobacco, a device for ejecting the severed charge horizontally from the compacted column, and mechanism for relieving the pressure on the severed bunch charge during the removal by said device, said means including a bottom plate engaging the bottom of said column, and said device operating to lower said bottom plate to create a clearance during the ejection of the severed charge from the column.

4. In a cigar machine, the combination with 10 means for compacting a vertical column of laminated filler tobacco, of a horizontal knife for severing a bunch charge from one end of the

compacted column of tobacco, a device for removing the severed charge in a horizontal direction from said column, and means for relieving the compression of the severed charge during the removal thereof from the column, said relieving means including an abutment engaging the outer horizontal face of the charge, and a device for moving said abutment in a direction away from said charge to relieve the pressure of the abutment on the severed charge during the ejection thereof.

JOHN F. HALSTEAD.
